UNITED STATES PATENT OFFICE.

WALTER C. KIESEL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE HAND SET.

1,425,977.

Specification of Letters Patent. Patented Aug. 15, 1922.

Application filed December 8, 1919. Serial No. 343,321.

To all whom it may concern:

Be it known that I, WALTER C. KIESEL, a citizen of the United States, residing at New York, in the county of New York, State of New York, have invented certain new and useful Improvements in Telephone Hand Sets (for which I have filed an application in Austria A-497-16, February 4, 1916), of which the following is a full, clear, concise and exact description.

This invention relates to telephone apparatus and more particularly to hand-sets.

The principal object of the invention is to provide an improved form of hand-set capable of satisfactory use under a wide range of conditions. Telephonic hand-sets are used under a variety of conditions and are often subjected to exceedingly rough treatment. For these reasons it has been the general practice to make the handle of these sets and the transmitter and receiver casings of metal. While such constructions are satisfactory under some conditions, it has nevertheless been found that sets having metallic handles are decidedly uncomfortable when used in cold locations. This is particularly true on taking hold of the handle with the bare hand when the temperature of the handle is below freezing, and often results in injury to the user due to his hand freezing fast to the handle. Similar injuries are also found to occur to the ear and lips of the user with handsets employing metallic ear and mouth pieces.

The use alone of non-metallic substances such as hard rubber or bakelite for these parts while satisfactory in preventing freezing between the flesh of the user and such parts, yet so reduces the mechanical strength of the handle as compared with former metallic handles that they do not possess the necessary strength to successfully withstand the extremely severe usage to which they are subjected, as, for example, in front line military operations. The necessity of providing space within the handle throughout its length for the running of the usual cord conductors has also been a further factor in reducing the strength of such handles.

The present invention overcomes this mechanical difficulty by embedding within the handle during its manufacture one or more conducting strips which in addition to serving as electrical conductors also serve to reinforce and to thus strengthen the handle.

The electrical conductors which were formerly a cause of weakness in the handle are thus converted into a source of strength and further provide a construction in which all the connections of the usual cord conductors can be made at one end of the set. By the use of insulating material for the handle, the necessity of separately insulating the conducting strips from each other and from the handle is no longer present; this being done naturally by the enclosure of the strips by the material of the handle during manufacture.

As a further improvement in hand-sets the present invention also contemplates the manufacture of the transmitter or receiver casing or both of the same non-metallic material as the handle and in one piece therewith.

Referring more specifically to the drawings, Fig. 1 is a longitudinal section on the line I—I of Fig. 2 of a hand-set embodying the present invention; Fig. 2 is a rear elevation thereof with the housing for the cord conductors removed; Fig. 3 is a longitudinal section of a hand-set having the transmitter and receiver casings of the same material as the handle and formed in one piece therewith; and Fig. 4 is a fragmentary section of a modified construction in which the fastening means for securing the receiver casing to the handle also serve as electrical conductors between the reinforcing strips and the electrical unit of the receiver.

The hand-sets shown comprise a handle of non-metallic material, preferably of hard rubber, bakelite or other suitable insulating material capable of being formed into shape by pressing or moulding. A pair of spaced conducting strips 6 and 7, preferably of brass, extend longitudinally of the handle and are firmly embedded in and surrounded by the material of the handle in the manufacture of the latter. These strips, while shown in Figs. 1, 2 and 3 as of circular cross section may be of any suitable cross sectional shape and area to provide the desired amount of reinforcement; Fig. 4 showing said strips as of rectangular cross section. The material of the handle surrounding the strips 6 and 7 insulates the one from the other, while the spacing of the strips in addition also provides more uniform reinforcement of the handle.

In the form shown in Figs. 1 and 2, a

separate receiver casing 8, which may be the usual metallic casing or one of non-conducting material, is secured to the upper end of the handle 5 by means of screws 9 extending through the rear wall of the casing and engaging threaded bushings 10 embedded in the handle. A transmitter casing 11 is also shown as similarly secured to the lower end of the handle 5 through the medium of screws 12 and bushings 13. Like the receiver casing 8, the transmitter casing 11 may be of metal or of non-conducting material.

The receiver casing 8 contains a receiver unit 14 of any desired type and short conductors such as 15 serve to connect the opposite terminals of this unit with the conducting strips 6 and 7 through which the receiver unit is connected in its operating circuit. Electrical connection between the conductors 15 and the strips 6 and 7 can be made in a variety of ways and as shown in Fig. 1 is accomplished by extending a threaded portion 16 of the strips 6 and 7 through the receiver casing 8 and employing a nut and washer on this threaded portion to secure its proper conductor 15 thereto. When used with a metallic receiver casing 8 the threaded portion 16 of at least one of the strips 6 and 7 should be insulated from this casing by an insulating bushing 17 in order to prevent short circuiting of the receiver unit 14 by the casing 8. When the receiver casing is of insulating material such as the receiver 18 of Fig. 3, the use of insulating bushings is, of course, unnecessary.

Electrical connections between the lower ends 19 of the strips 6 and 7 and the cord conductors of the usual flexible cord (not shown) used with hand-sets, may also be made in a similar manner, as illustrated in Figs. 1, 2 and 3, although other suitable fastening arrangements may be employed. One such arrangement is shown in Fig. 4, wherein the strips 6 and 7 instead of having threaded portions extending outside of the handle are each threaded as at 20 to receive a screw 21 which may be used to directly engage another conductor such as 22 which it is desired to electrically connect with such strip. With this arrangement the screws 21 may also be used to hold the casing 23 to the handle 5, taking care to insulate at least one of these screws from the casing if the latter be of conducting material.

The transmitter casing 11, and the transmitter casing 24 integral with the handle 5 as shown in Fig. 3, each contain a transmitter unit 25 of any desired type and electrical connections are made therewith through flexible conductors 26 and 27 secured to studs 28 embedded in and extending through the lower portion of the handle 5. The rear ends of these studs 28 are threaded and provided with nuts and wash-

ers through which connection can be made between the cord conductors of the usual flexible cord (not shown), or other circuit connections of the hand-set itself according to the requirements of any particular circuit with which the set is to be used. When used with a conducting casing such as the casing 11 of Fig. 1, at least one of the studs 28 must be insulated therefrom and an insulating bushing 29 is shown for this purpose.

The ends 19 of the strips 6 and 7 and the rear ends of the studs 28 are closely grouped at the lower end of the handle to facilitate connection with the flexible cord and are protected by a housing 30 secured to the handle 5 by a screw 31 engaging a threaded bushing 32 embedded in the handle. This housing 30 may, if desired, be formed of metal as illustrated in Fig. 1, as may also the casings 8 and 11, inasmuch as there is little chance of these parts being contacted with in the use of the instrument; but the ear piece 35 and the mouthpiece 36 as well as the handle 5 are all preferably of non-metallic substances such as hard rubber or bakelite in order to prevent injury to the user from contact therewith, as previously explained.

By employing the general construction shown in Fig. 1, but forming the housing 30 and the casings 8 and 11 of non-metallic material a hand-set is produced in which all the exposed parts would be of non-metallic material, and with such a hand-set danger of injury to the user from freezing his flesh thereto is entirely eliminated and a set of uniform appearance provided.

The same advantages are also present in the construction shown in Fig. 3 wherein the casings 18 and 24 are formed of the same material as the handle 5 and in one piece therewith. This form has the further advantage of simplicity and materially reduces the cost of the set and the amount of labor necessary for its assembly, due to its unitary construction. Such a set also, due to there being no metallic parts exposed, eliminates any danger of electric shock to the user.

What is claimed is:

1. A hand-set handle having a rigid electrically conducting strip embedded in and extending longitudinally of the handle to reinforce the handle and designed for inclusion in the electrical circuit of the hand-set.

2. A hand-set handle having a plurality of rigid electrical conducting strips embedded in and extending longitudinally of the handle in spaced relation with one another to reinforce the handle and each designed for inclusion in the electrical circuit of the hand-set.

3. A hand-set handle of insulating material having a bare electrically conducting strip embedded in and extending longitudi-

- nally of the handle to reinforce the handle and designed for inclusion in the electrical circuit of the hand-set.
4. A hand-set handle of insulating material having a plurality of bare electrically conducting strips embedded in and extending longitudinally of the handle in spaced relation to one another to reinforce the handle and each designed for inclusion in the electrical circuit of the hand-set.
5. A hand-set handle formed of molded insulating material having an electrically conducting strip molded in and extending longitudinally of the handle to reinforce the handle and designed for inclusion in the electrical circuit of the hand-set.
6. A hand-set handle formed of molded insulating material having a plurality of electrically conducting strips molded in and extending longitudinally of the handle in spaced relation to each other to reinforce the handle and each designed for inclusion in the electrical circuit of the hand-set.
7. A hand-set comprising a receiver casing, a transmitter casing, an electrical device in one of the casings, a solid handle extending between and uniting the casings, and a conducting strip embedded in and extending longitudinally of the handle between the casings, to reinforce the handle and forming a part of the electrical circuit of the device in one of the casings.
8. A hand-set comprising a transmitter casing, a receiver casing, an electrical device in one of the casings, a solid handle of insulating material extending between and uniting the casings, and an electrically conducting strip embedded in and extending longitudinally of the handle between the casings to reinforce the handle and having a portion extending into the casing containing the electrical device and forming a part of the electrical circuit of the device.
9. A hand-set comprising a transmitter casing, a receiver casing, an electrical device in one of the casings, a solid handle of insulating material extending between and uniting the casings, and an electrically conducting strip embedded in and extending longitudinally of the handle between the casings to reinforce the handle having one end portion extending into the casing containing the electrical device and electrically connected therewith and having the other end portion extending exteriorly of the handle for electrical connection in the circuit of the electrical device.
10. A hand-set comprising a handle, an electrically conducting strip embedded in and extending longitudinally of the handle to reinforce said handle and designed for inclusion in the electrical circuit of the hand-set, and a transmitter casing formed in one piece with said handle.
11. A hand-set comprising a handle, an electrically conducting strip embedded in and extending longitudinally of the handle to reinforce said handle and designed for inclusion in the electrical circuit of the hand-set, and an apparatus casing formed in one piece with said handle.
12. A hand-set comprising a handle, an electrically conducting strip embedded in and extending longitudinally of the handle to reinforce said handle and designed for inclusion in the electrical circuit of the hand-set, a transmitter casing, and a receiver casing, the handle and the transmitter and receiver casings being all formed together in one piece.
13. A hand-set comprising a solid handle, a transmitter casing, a receiver casing, the handle and the transmitter and receiver casings being of like material and all formed together in one piece, and a strip of electrically conducting material embedded in and extending longitudinally of the handle between the casings to reinforce the handle and to form a part of the electrical circuit of the hand-set.

In witness whereof, I hereunto subscribe my name this 4th day of December A. D., 1919.

WALTER C. KIESEL.
